CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA

COMMUTATOR

Application filed July 11, 1928. Serial No. 291,748.

My invention relates to commutators for dynamo-electric machines, and more particularly to the arrangement of parts in commutator cylinders for machines of high capacity.

6 In the construction of large commutators, it is necessary that every step be taken to construct a commutator in which the associated parts are combined to the best advantage in order to allow for stresses set up by the expansion of parts and by centrifugal action.

Since the commutator bars carry current, they are heated and expand, leaving the commutator cylinder with a rough surface and with the parts somewhat distorted. In large 15 commutators, this expansion is considerable. The copper, having a greater coefficient of expansion and being run hotter than the associated parts, will tend to stretch the bolts which hold the clamping rings.

20 It is an object of my invention to provide a commutator in which the parts are so combined that compensation for expansion of the commutator bars is provided and the initial stresses in the commutator cylinder are thereby maintained throughout any range of temperature that may develop.

It is another object of my invention to provide a commutator in which the commutator bars are given initial stresses upon assembling 25 in order to prevent bulging in the middle by the action of centrifugal force.

It is a further object of my invention to provide each commutator bar with a relieved edge-portion along the inner edge of the inwardly-projecting portion in order to prevent concentration of stresses in the V-recesses of the bars because of distortion of the V-ring.

30 A better understanding of my invention may be had by reference to the following description, taken with the accompanying drawing, in which

Figure 1 is a longitudinal sectional view of a portion of a commutator cylinder in the form now preferred by me, and

45 Fig. 2 is a similar view of another commutator cylinder embodying some of the features of my invention.

50 In Fig. 1, is illustrated a spider 5 which is usually of cast steel and has a plurality of

holes 6 extending longitudinally near the periphery thereof and circumferentially spaced therearound. Commutator bars 7 having radially-extending dovetail portions 8 and V-shaped recesses 9 and 10, are maintained on the surface of the spider by clamping rings 11 and 12, having inwardly-extending V-shaped portions which are wedged into the recesses 9 and 10 and are insulated therefrom by mica spacers, 13 and 14. The V-rings 55 11 and 12 are maintained against the spider by a plurality of bolts 16 which are located in the holes 6 in the spider 5 and project from one end.

The portions of the bolts 16 within the 60 holes 6 are surrounded by sleeves 17 which are preferably made of a non-expansive material, such as invar steel. The head 18 of each bolt 16 engages the corresponding end of the sleeve 17 to force its other end against 65 a shoulder 19.

The clamping bolts 16 are alternately disposed around the commutator cylinder so that one half of the bolt heads 18 are located at one end and the other half are located at 70 the other end.

75 Since copper has a greater coefficient of expansion than the material of the bolts and V-rings, there is considerable pressure created in a longitudinal direction against 80 the V-rings. The V-rings being of different material and being run much cooler than the copper bars, they will not expand the same amount, and, consequently, the V-rings 85 become distorted while the bolts stretch and bend inwardly. The spider is also at a lower temperature than the copper approximating that of the V-rings and, therefore, expands longitudinally a distance much less than that of the commutator bars.

90 The bolts are placed under considerable stress and, since they are placed in a non-expansive sleeve, there will be no pressure acting against the heads 18 to move them outwardly from the holes. Consequently, 95 the bolts are allowed free movement to the left, a distance equal to the expansion of the spider from the vertical axis X-Y. In this manner, the total expansion of the parts may be considered as the summation of one 100

half of the expansion of the spider and the expansion provided by a bolt of increased effective length.

The enormous intensity of the stresses which are set up by the longitudinal expansion may be better appreciated by a mathematical discussion.

If it be assumed that copper bars expand 1.73 mils per inch under a 100° C. rise, and steel expands only .55 mils per inch under 50° C. rise, the difference will be 1.18 mils per inch, which must be compensated for in the construction of the commutator. Hence, a commutator bar 16 inches in active length will expand approximately 19 mils. Assuming the bolts to be 26 inches long, the change in length per inch of length becomes .00077, which multiplied by the modulus of elasticity for steel or 3×10^7 , gives a unit stress 22,000 lbs. per square inch set up in the bolts. By allowing movement of the bolts with expansion of the spider, and by the utilization of alternate bolts to get, in effect, bolts which are substantially twice the length of the commutator cylinder, I manage to reduce the stress in the bolts to that of their initial, cool condition, and thereby obtain a commutator cylinder in which the stresses are kept in equilibrium, regardless of changes in temperature.

With commutator cylinders rotating at high speeds, there is a tendency for the bars to bulge out in the middle, thereby creating a rough surface, the amount of bulging depending upon the length of the commutator cylinder. Another feature of my invention prevents such action.

It will be noted that the middle part of the outer surface of the spider has a larger diameter than its ends and that the tapering begins at the ends 21 and 21a of a cylindrical middle portion.

In assembling the commutator bars, they are bent to engage the spider surface, thus setting up initial stresses in the bars which are slightly greater than any centrifugal stresses which will be exerted at the middle of the commutator cylinder. The commutator-cylinder surface is then finished true to its axis.

That portion of the commutator bar which rests on the top of the V-ring is cut at an angle A which is smaller than the angle B of the V-ring. Because of the difference between angles A and B, when the V-rings are forced into the recesses 9 and 10, they clamp the bars down over the ends 21 and 21a on the surface of the spider 5.

The commutator bars are not only prevented from bulging at the middle but are also given initial stresses at their ends, so that the entire surface of a commutator cylinder constructed in this manner is prevented from getting rough because of centrifugal force.

Under abnormal conditions, there is a tendency for the V-rings to distort, the inner edge working inwardly and a great pressure being concentrated at points in the annular recesses of the commutator bars. In order to prevent concentration of force, I provide relieved portions 23 on the bottom edge which will allow the extended portions to drop down an amount corresponding to the distortion of the V-rings, and, at the same time, leave the pressure distributed as nearly as possible uniformly over all surfaces of the recess.

There is also a tendency for the V-rings to expand circumferentially, and, if the inwardly projecting portions 24 and 25 on the respective V-rings are maintained against the under edge of the spider rim, a great deal of friction will result and the spider will thereby be prevented from expanding horizontally. I make allowance for such expansion by undercutting the inner faces of the projecting portions 24 and 25 of the V-rings and providing grooves in the undercut faces to receive felt rings 26 and 27, respectively.

In Fig. 2, some of the features described above are taken care of in a slightly different manner, and, at the same time, other features are shown.

A spider 31 is surrounded by a brass cylinder 32 on the outer surface of which are disposed the copper commutator bars 33 which are separated from the cylinder 32 by the usual mica insulation 34.

The V-rings 35 and 36 are maintained in the recesses 37 and 38 of the commutator bars by bolts 39 which are inserted in the ends of the cylinder 32. The bolts 39 are provided with sleeves 41 of invar steel in order to increase their expansion length, giving them nearly twice the expansion of bolts utilized heretofore.

The brass cylinder 32 preferably has its inner periphery fitted into a wedge-shaped groove 42 provided in the outer surface of the spider. The brass, being of nearly the same coefficient of expansion, will expand radially, nearly the same distance as the copper, and, in that way, serve to fill in a gap which tends to form between the spider surface and the bottoms of the copper bars, but this expansion is not quite enough to keep the stresses uniform throughout the structure. By reason of the wedge-shaped groove 42, I provide

means whereby the clearance is required to take place between the brass and the spider element. The brass not only expands radially, but expands longitudinally, and, therefore, the sloping surfaces 43 and 44 tend to creep up on the wedge walls of the groove since a resultant sliding force acts along the line of contact, and the brass ring is thereby kept against the bottom surfaces of the copper commutator bars.

It will be understood that various modifications may be made in the arrangement of parts, and it is intended to cover herein such modifications as fall within the spirit and scope of my invention as defined in the appended claims.

I claim as my invention:

1. A commutator comprising a cylindrical spider, commutator bars disposed on said spider and insulated therefrom, clamping rings engaging the ends of said bars, bolts for forcing said rings against the ends of said bars, and sleeves of non-expansive material surrounding portions of said bolts and abutting against a portion of said spider.

2. A commutator for a dynamo-electric machine comprising a cylindrical spider having longitudinally-extending holes, commutator bars disposed on said spider, clamping rings, and means for clamping said rings comprising bolts located in said holes and projecting therefrom at one end, sleeves of non-expansive material surrounding said bolts within said holes.

3. A commutator for a dynamo-electric machine comprising a cylindrical spider having longitudinally-extending holes, commutator bars disposed on said spider, clamping rings adapted to engage the ends of said bars, means for clamping each of said rings in end engagement with said bars comprising bolts disposed in said holes, each of said bolts being longer than the distance between said clamping rings, and sleeves cooperating with said bolts whereby the stresses set up by expansion of said bars is transferred to members having substantially twice the active length of said commutator bars.

4. In a commutator, the combination of a cylindrical spider having a plurality of holes extending therethrough, commutator segments, V-rings disposed at the respective ends of said segments, means for clamping said V-rings to said segments in such manner as to decrease the strain on said bolts by axial expansion of said segments, said means comprising bolts extending through said holes, and sleeves of material dissimilar from said bolts surrounding the portions of the bolts within said holes.

5. In a commutator, the combination of a cylindrical spider having a plurality of holes extending therethrough and adjacent to the periphery thereof, commutator bars disposed on said spider, V-rings, and means for clamping said V-rings to said bars comprising bolts disposed in said holes, adjacent bolts extending in opposite directions and the portions of the bolts lying within said holes being surrounded by sleeves of non-expansive material, thereby increasing the effective lengths of said bolts to decrease the strain at any section by axial expansion of said bars.

6. In a commutator, the combination of a

spider having longitudinally-extending holes therethrough, commutator bars surrounding said spider and insulated therefrom, clamping rings engaging the ends of said bars, and means for clamping one of said rings comprising bolts located in some of said holes, and means for clamping another of said rings comprising bolts located in others of said holes, and sleeves surrounding the portions of said bolts lying within said holes to thereby increase the effective lengths of said bolts to which stresses caused by the expansion of the commutator bars are subjected.

7. A commutator member for a dynamo-electric machine comprising a cylindrical spider having longitudinally-extending holes, commutator bars disposed on said spider, clamping rings, and means for clamping said rings comprising bolts located in said holes, and sleeves of invar steel surrounding the portions of the bolts lying within said holes.

8. A commutator member comprising a spider having a substantially cylindrical surface, the mid-diameter of which is slightly greater than the end diameters, commutator bars having annular recesses in the respective ends thereof, the outer side wall of each recess having a slight angle with the commutator axis, a clamping ring having a wedge-shaped portion to engage said recess, the outer surface of said portion being inclined at an angle slightly greater than the angle of said sidewall, means of clamping said rings whereby the angular wall portions conform to each other, each of said bars being bent down upon said spider surface and initially stressed, the end regions of said commutator being bound to said rings by the clamping action thereon.

9. In a commutator, the combination comprising a cylindrical spider, commutator bars disposed on said spider and having V-shaped recesses in the end-portions, V-rings adapted to engage said recesses, means for clamping said rings so as to cause the latter to hold the bars against the surface of said spider, the bottom edges of said bars having relieved portions spaced from the spider at the ends of the bars, whereby, upon distortion of said rings, the ends of the bars may deflect an amount corresponding to the distortion of the rings.

10. In a commutator member, the combination comprising a cylindrical spider, a brass cylinder surrounding said spider, commutator bars disposed on said cylinder, V-rings engaging the ends of said bar, means for clamping said rings comprising bolts having sleeves of non-expansive material surrounding portions thereof, said brass cylinder substantially compensating for circumferential expansion of the bars and tending to fill any space that may be left between said bars and said spider upon change in temperature of said commutator member.

11. In a commutator, the combination com-

prising a cylindrical spider having a grooved surface, a brass cylinder surrounding said spider and adapted to fit said grooved surface and engage inclined surfaces near the outer ends thereof, commutator bars disposed on said cylinder, V-rings engaging the ends of said bars, and means for clamping said rings, said commutator bars being maintained in contact with said brass cylinder at any commutator temperature by circumferential expansion and radial movement due to longitudinal expansion acting against said inclined surfaces.

12. A commutator cylinder comprising copper bars having V-grooves in their ends, V-rings engaging said grooves, a supporting spider for said commutator bars and V-rings, bolts for securing said V-rings to said supporting spider, and spacing means having a very low coefficient of expansion, as compared to the bolts, interposed between the ends of the bolts so as to increase the bolt length.

13. The invention, as defined in claim 12, characterized by the fact that alternate bolts extend to opposite V-rings.

14. The invention, as defined in claim 12, characterized by the fact that alternate bolts extend to opposite V-rings and the inner bolt-heads of the bolts which extend to one V-ring extend into close proximity to the other V-ring, whereby substantially the maximum practicable length of bolt is obtained.

In testimony whereof, I have hereunto subscribed my name this 5th day of July, 1928.

CHRISTIAN AALBORG.
